UNITED STATES PATENT OFFICE.

HORATIO L. PEIRCE, OF TAUNTON, MASSACHUSETTS.

IMPROVEMENT IN RING FOR SPINNING-MACHINE.

Specification forming part of Letters Patent No. 90,956, dated June 8, 1869.

To whom it may concern:

Be it known that I, HORATIO L. PEIRCE, of Taunton, in the county of Bristol and State of Massachusetts, have invented certain new and useful Improvements in Spinning-Rings; and I hereby declare the following to be a full, clear, and exact description of the same, reference being had to the accompanying drawings.

My invention essentially consists in steel-lining that part of a spinning-ring upon which the traveler runs, or upon which it wears most, as hereinafter described, and it is equally applicable to the manufacture of new rings and to the repairing of old ones.

Ordinary spinning-rings made of case-hardened iron are very defective for many reasons. They are soft and will soon become worn, and their temper cannot be depended on, as they wear unevenly and become rough. Owing to this, the thread is liable to break, and not only is there a waste of yarn, but the travelers are also injuriously affected. In fact, it is of little avail that the machine and frame are made perfect, so long as the ring and traveler are not adapted for the work.

When there is a rough or imperfect ring, a lighter traveler must be employed than would be necessary were the ring smooth and true; and in case of a light traveler with an ordinary ring, although the draft may be right when the bobbin is empty, yet as the bobbin fills the draft decreases, thus allowing the yarn to kink and to produce a soft bobbin.

The object I have in view, in the invention above named, is to obviate these and like defects.

In carrying my invention into effect, I proceed as follows: I turn out or otherwise form a groove, *a*, in the spinning-ring *A*, at the point where, ordinarily, the inside flange of the ring or race is formed. I then take a steel wire, *b*, of round, flat, or other required form, and shape the ends so that they will fit or dovetail together; and then, having heated the spinning-ring, spring the steel hoop or ring into the groove *b*, so as to form the inside flange of the race, as shown in perspective, Figure 1, and in section, Fig. 2, after which the two are to be soldered together. The ring thus formed is then hardened.

The advantages attending the use of a ring of this construction are many:

First, as it is made of cast-steel, it can be hardened and tempered better than iron can be case-hardened. In fact, the latter cannot be hardened, all attempts at hardening having practically failed, because of the tendency of the iron to break and split.

Second, the steel-lined ring will wear much longer than the ordinary ring. The old rings always wear upon the inside flange, against which the traveler almost exclusively bears, and so long as the inner flange remains smooth and true the outer flange remains intact. It will be seen that this is provided for in my improved ring by the arrangement of the steel ring *b*.

Third, as the flange remains smooth and true, the traveler runs with greater ease. There is no waste of yarn, and need be no variation in the weight of the traveler.

Fourth, the flange of the ring can be widened without great expense and with little trouble by taking out the lining and putting in a wider lining whenever desired.

Fifth, the invention is adapted to the repairing of old rings as well as to the manufacture of new ones. Instead of throwing away an old ring, it can be made as good or better than a spinning-ring of ordinary make by turning out the inside flange and forming the groove *a* as above described, after which the steel ring *b* can be applied, so that in this respect alone, by turning the old rings to account, the invention is exceedingly valuable.

Having now described my invention, and the manner in which the same is or may be carried into effect, what I claim, and desire to secure by Letters Patent, is—

A spinning-ring having a steel lining constructed and applied substantially as herein described.

In testimony whereof I have signed my name to this specification before two subscribing witnesses.

HORATIO L. PEIRCE.
